UNITED STATES PATENT OFFICE

WALDEMAR L. LINDGREN, OF WAUKEGAN, ILLINOIS, ASSIGNOR OF ONE-HALF TO JOHN E. ERICSSON, OF CHICAGO, ILLINOIS

DISH WASHING APPARATUS

Application filed August 14, 1928. Serial No. 299,485.

My invention is concerned with dish washing apparatus of the type shown in my companion application No. 299,486, filed Aug. 14, 1928, now Patent No. 1,798,425, dated March 31, 1931, and is more especially designed to produce dish-washing apparatus of the type referred to which shall be power-operated and which, although permanently secured in a portion of the sink, can be tilted up to get at the other side for cleaning, etc.

To illustrate my invention, I annex hereto three sheets of drawings, in which the same reference characters are used to designate identical parts in all the figures, of which,—
15 Fig. 1 is a top plan view of a sink having my invention applied thereto;

Fig. 2 is a front elevation of the same, partly in section, on the line 2—2 of Fig. 1;

Fig. 3 is a view on a larger scale, showing 20 the dish-washing apparatus proper tilted up so that the under side can be gotten at;

Fig. 4 is a detail in cross section on the line 4—4 of Fig. 2, but on a larger scale;

Fig. 5 is a detail in section on the line 5—5 25 of Fig. 1, but on a larger scale; and

Fig. 6 is a detail in section on the line 6—6 of Fig. 4.

In carrying out my invention in its preferred form, I preferably employ what I 20 may call a duplex sink having the right-hand portion 10 of an ordinary sink construction, with the customary hot and cold water faucets 11 and 12 co-operating therewith in the customary manner. The left-hand member 13, with which the dish-washing apparatus is 25 particularly associated, is of a similar construction except as to the faucets, and the two sinks are preferably separated by a rib 14 extending between them and made of the same 30 material, and, in fact, constituting a portion of the body of the sink. The two halves will be provided with the drain pipes 15 and 16.

The dish-washing apparatus proper is constructed of two symmetrical side-frame members 17, which are connected at the left-hand 45 end by a cross piece 18 screwed thereon, while the right-hand ends are preferably connected by the table piece 19 having the triangular side members 20 suitably secured, by bolts or otherwise, to the adjacent ends of the side

frames, so that a rigid structure is secured. The right-hand end is supported by the pair of legs 21, but the left-hand end is mainly supported by the connections to be described for the operating shaft 22, which has the 55 sprocket wheels 23 connected thereto toward its ends, but on the inside of the frame members 17. The hot-water pipe 24 extending through the side wall is supplied with the hand cock 25, from which extends a horizontal sleeve member 26 having the flange 27 adjacent the cock 25, preferably forming a part of the sleeve, while the other end has the ring flange 28 threaded thereon to hold the transverse, cylindrical end 29 of the substantially-horizontal, hot-water pipe member 30 in place. The sleeve 26 is provided with an outlet 31 which co-operates with the pipe member 30 when the apparatus is in the operative position shown in Fig. 2, so that hot 60 water is carried to the two spray pipes 32 and 33 which terminate in the spray heads 34 and 35, which have their upper surfaces 36 curved in both vertical sections and perforated, so that a spray of water is thrown up 65 and sidewise to contact with the dishes on the skeleton conveyor. This conveyor is formed of a series of rods 37 connected by the links 38 so as to produce an endless chain, the rods 37 adjacent the links co-operating with 70 the recesses in the sprocket wheels 23 by which they are driven, and with the similar recesses in the similar sprocket wheels 39 secured to or mounted to rotate on the shaft 40 secured in suitable bearings in the right-hand end of the 75 side frame members 17.

With the construction described, it will be obvious that as the shaft 22 is rotated clockwise, the upper run of the skeleton frame will travel from left to right, the links 38 therefore riding on the flanges 40 formed on the inner face of the side frame 17 for this purpose. The sleeve member 26 has the bearing 41 in its outer end, which receives the adjacent end of the shaft 22, which also has a short bearing 42 therefor formed as a part of the outside frame 17. The other end of the shaft 22 has the bearing 43 in the side frame on that end, and splined on the shaft adjacent said bearing 43 is the worm gear 100

wheel 44 by which the shaft is driven by means to be subsequently described. The shaft 22 extends on through a bearing opening in the housing 45 for the worm gear wheel 44 and its associated worm 46, and has its end journaled in the bearing 47 formed in the circular bearing piece 48 which is secured in the recess 49 formed in the side of the sink and held in place by the lock nut 50 threaded thereon.

With the construction thus far described, it will be seen that the frame can be swung from the normal operating position shown in Fig. 2 up to the position shown in Fig. 3, where it may be held by the wire bail 51 having its ends journaled at 52 on the side frames, and having its cross piece provided with the two loops 53 for a purpose to be described. When the washing apparatus is tilted up, as shown in Fig. 3, the bail 51 is of the proper length so that its ends will engage the rib 14 at its base and hold the mechanism in its elevated position. Above the cock 25 is a similar cock 54 connected to the hot-water pipe 55 led in from the wall, and provided with the short pipe 56 which connects to the elbow 57, which has connected thereto the horizontal pipe 58, which has the T 59 therein and the elbow 60 at its end, which T and elbow are connected to the swiveled connections 61 and 62, which have the elbows 63 and 64 connected to the pipes 65 and 66 of the spray members 67 and 68, similar to the spray members 34 and 35 except that their perforated surfaces face downwardly so that both the tops and bottoms of the dishes passed beneath the spray members are subject to the action of the cleansing water. The two spray members 34 and 67 have a soap-holding structure associated therewith, such as is described in the aforesaid companion application No. 299,486, so that the dishes are first subjected to a spray of hot suds, after which they are subjected to a spray of clean water from the lower spray member 35 to the right and the upper spray member 68.

When the apparatus is in use, the spray members 67 and 68 are extended transversely of the apparatus, as seen in Fig. 1, but when it is to be elevated to the position shown in Fig. 3, they will be swung around until they are in line with and beneath the pipe 58, where they are not in the way of the framework when it is swung up to the position shown in Fig. 3.

To confine the water sprayed upon the dishes within proper limits, I preferably provide a cover mechanism which consists of two halves, each of which is composed of a horizontal section 69 and a vertical section 70 hinged thereto, the top members 69 co-operating and being provided with apertures through which the loops 53 extend upwardly 95 when the covers are in place, so that by turn-

ing the catches 71, seen in Fig. 1, into place, the covers are supported on the wire bail 51, as indicated in Fig. 2. This bail is on the inside, and the vertical portions 70 of the cover extend down to the top edges of the sink member 13, to which they are detachably hinged, as seen in Fig. 4, the hinges between the parts 69 and 70 being provided so that they can be folded up when desired. It will be obvious that in use the cover members are 75 in place, but when the apparatus is to be tilted up to clean, they have first to be removed by loosening the hooks 71, after which they can be detached. Of course, these covers have recesses in the horizontal portion 69 to 80 accommodate the spray members 67 and 68, the perforated portions of which extend below the tops of the covers.

To drive the mechanism thus far described, I preferably employ a small electric motor 72, which is suspended from the under side of the sink near its edge, the sink being preferably provided with an outwardly extending portion 73 to position properly the motor relative to the dish-washing mechanism. 90 The armature shaft 74 of the motor extends up through a bearing aperture in the bottom of the sink 13 and has secured on its upper end the clutch member 75, which in use cooperates with the clutch member 76 secured on the lower end of the vertical shaft 77 journaled in the bearings 78 and 79 formed in the gear casing 80 secured to the side of the adjacent side frame 17, as seen in Fig. 5. This gear casing 80 has journaled therein one end of a longitudinal shaft 81, which has secured thereon the worm gear wheel 82 meshing with the worm gear 83 secured on the shaft 77. The other end of the longitudinal shaft 81 is journaled in the lower portion of the gear casing 45 and has secured thereon the worm 46 previously mentioned as meshing with the worm gear wheel 45. With the connections thus described, it will be obvious that the rotation of the armature of the motor 72 will cause the shaft 22 to rotate at a very much reduced speed owing to the double worm and gear reduction, and it will also be obvious that when the frame is tilted up, the motor is disconnected, but is automatically connected when the frame is lowered.

The outlet 31 co-operating with the pipe member 30 is preferably of a size sufficient to admit water to the pipe member 30 when it is swung upward as shown in Fig. 3, so that the spray from the heads 34 and 35 can be utilized in washing the machine itself when it is swung up for that purpose. It will be obvious that the spray with the machine swung up, after deflection, will strike portions thereof at different angles from those at which it strikes them when the machine is down and in operation, and will also strike other portions of the machine.

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States, is:

1. In dish-washing apparatus, the combination with a sink, of a frame pivoted at one end thereof in said sink with the other end normally supported thereby, a skeleton conveyor carried by said frame, spraying mechanism discharging on the conveyor, a motor supported by the sink, and clutch mechanism between the motor and the conveyor comprising a driven member operatively connected to the conveyor and a driving member connected to the motor, the said members being juxtaposed so that they engage each other when the frame is in its lowered position and are automatically disengaged when the frame is tilted upward on its pivot.

2. In dish-washing apparatus, the combination with a sink, of a frame pivoted at one end thereof in said sink with the other end normally supported thereby, a skeleton conveyor carried by said frame, spraying mechanism discharging on the conveyor and movable with said frame, means for driving the conveyor, a water-supply pipe in alignment with the frame pivot, and a conduit communicating with the spraying mechanism and with the supply pipe and swiveled on the latter.

3. In dish-washing apparatus, the combination with a sink, of a frame pivoted at one end thereof in said sink with the other end normally supported thereby, a horizontally-movable skeleton conveyor carried by the frame, spraying members located below said conveyor and moving with the frame, a water-supply pipe in alignment with the frame pivot, and a conduit communicating with the spraying members and with the supply pipe and swiveled on the latter.

4. In dish-washing apparatus, the combination with a sink, of a frame pivoted at one end thereof in said sink with the other end normally supported thereby, a horizontally-movable skeleton conveyor carried by the frame, spraying members located above said conveyor in proximity to the top of the frame, water-supply piping connected to said members, and vertical swivels in said piping so that the members may be swung laterally out of the way of the frame to permit of its being tilted up.

5. In dish-washing apparatus, the combination with a sink, of a frame pivoted at one end thereof in said sink with the other end normally supported thereby, a skeleton con-

veyor carried by said frame, spraying mechanism discharging on the conveyor and movable with said frame, a water-supply pipe in alignment with the frame pivot, a conduit communicating with the spraying mechanism and with the supply pipe and swiveled on the latter, a motor supported by the sink, and clutch mechanism comprising a driven member operatively connected to the conveyor and a driving member connected to the motor, the said members being juxtaposed so that they engage each other when the frame is in its lowered position and are automatically disengaged when the frame is tilted upward on its pivot.

6. In dish-washing apparatus, the combination with a sink, of a frame pivoted at one end thereof in said sink with the other end normally supported thereby, a horizontally-movable skeleton conveyor carried by the frame, spraying members located above and below said conveyor, a water-supply pipe in alignment with the frame pivot, a conduit communicating with the lower spray member and with the supply pipe and swiveled on the latter, piping connected to the upper spraying member, a vertical swivel in said last-mentioned piping so that the upper spraying member may be swung out of the way of the frame when it is tilted up, a motor supported by the sink, and clutch mechanism comprising a driven member operatively connected to the conveyor and a driving member connected to the motor, the said members being juxtaposed so that they engage each other when the frame is in its lowered position and are automatically disengaged when the frame is tilted upward on its pivot.

7. In dish-washing apparatus, the combination with a sink, of a frame mounted in the sink on a horizontal pivot at one end of the frame, dish-washing mechanism comprising a skeleton conveyor and spraying mechanism carried by said frame and operable in the horizontal position thereof, a removable cover for said dish-washing mechanism, and a bail pivoted on the frame and adapted to be either turned upwardly to have its transverse portion engage and hold the cover in place when the apparatus is in use or downwardly to have its transverse portion engage an abutment in the sink and hold the frame in its raised tilted position.

8. In dish-washing apparatus, the combination with a sink, of a frame mounted in the sink on a horizontal pivot at one end thereof, dish-washing mechanism comprising a spray member located above the frame, an opposed spray member located in the frame, piping connections for the spray members, a removable cover made of two hinged sheet-metal sections having apertures in their edges to accommodate the spray members and smaller apertures, a bail pivoted on the frame having

loops in its transverse portion and adapted to be either turned downwardly to have its transverse portion engage an abutment in the sink or to be turned upwardly to have its transverse portion engage and hold the cover in place when the apparatus is in use, and hooks pivoted on the cover and adapted to co-operate with the loops carried by the bail and extending up through said smaller apertures in the cover.

9. In dish-washing apparatus, the combination with an elongated sink having at one end two water cocks, one near the top and the other near the bottom of said sink, a pipe extending longitudinally of the sink, connected to the upper cock, and having two swivel connections, a pair of pipes connected to said swivel connections, and a spray member secured on the outer end of each of said last-mentioned pipes, which spray members by virtue of the swivel connections can be turned horizontally against the side of the sink or extended outwardly, of a frame pivotally supported at one end thereof in the sink with its pivot in axial alignment with the bottom water-cock, a pair of spray members carried by the frame, piping connections from the pair of spray members to the bottom water-cock so that they can be supplied with water, conveying means for the dishes carried by the frame, and means for moving the conveying means when the frame is in its horizontal position.

10. In dish-washing apparatus, the combination with an elongated sink having at one end two water cocks, one near the top and the other near the bottom of said sink, a pipe extending longitudinally of the sink, connected to the upper cock, and having two swivel connections, a pair of pipes connected to said swivel connections, and a spray member secured on the outer end of each of said last-mentioned pipes, which spray members by virtue of the swivel connections can be turned horizontally against the side of the sink or extended outwardly, of a frame pivotally supported at one end thereof in the sink with its pivot in axial alignment with the bottom water-cock, a pair of spray members carried by the frame, piping connections from the pair of spray members to the bottom water-cock so that they can be supplied with water, conveying means for the dishes carried by the frame, a motor suspended from the sink, and driving connections from the motor to the conveying means including clutch mechanism comprising a driven member operatively connected with the conveyor and a driving member connected to the motor, said members being juxtaposed so that they engage each other when the frame is in the lowered position and are automatically disengaged when the frame is tilted upward on its pivot.

11. In dish-washing apparatus, the combination with an elongated sink having at one

end two water cocks, one near the top and the other near the bottom of said sink, a pipe extending longitudinally of the sink, connected to the upper cock, and having two swivel connections, a pair of pipes connected to said swivel connections, and a spray member secured on the outer end of each of said last-mentioned pipes, which spray members by virtue of the swivel connections can be turned horizontally against the side of the sink or 75 extended outwardly, of a frame pivotally supported at one end thereof in the sink with its pivot in axial alignment with the bottom water-cock, a pair of spray members carried by the frame, piping connections from the pair of spray members to the bottom water-cock so that they can be supplied with water, conveying means for the dishes carried by the frame, a motor suspended from the sink, driving connections from the motor to the conveying means including clutch mechanism comprising a driven member operatively connected with the conveyor and a driving member connected to the motor, said members being juxtaposed so that they engage each other when the frame is in the lowered position and are automatically disengaged when the frame is tilted upward on its pivot, a two-part removable hinged cover for the frame, and a bail pivoted on the frame and adapted to be either turned upwardly to have its transverse portion engage and hold the cover in place when the apparatus is in use or downwardly to have its transverse portion engage an abutment in the sink 100 and hold the frame in its raised tilted position when it is being cleaned.

12. In dish-washing apparatus, the combination with a sink, of a cock in the side near one end thereof, a sleeve closed at one end 105 extending horizontally from the cock and having an outlet in the side and a shaft bearing in its closed end, a shaft bearing in the other side of the sink opposite the cock and in axial alignment therewith, a drive shaft 110 having its ends journaled in said bearings, a frame containing bearings on said shaft so that the frame is pivoted on the shaft, conveying mechanism in the frame driven by the shaft, spray mechanism carried by the 115 frame and discharging on the conveying mechanism, and a pipe leading from the spray mechanism and having its inlet end swiveled on the sleeve.

13. In dish-washing apparatus, the combination with a sink, of a cock in the side near one end thereof, a sleeve closed at one end extending horizontally from the cock and having an outlet in the side and a shaft bearing in its closed end, a shaft bearing in 125 the other side of the sink opposite the cock and in axial alignment therewith, a drive shaft having its ends journaled in said bearings, a frame containing bearings on said shaft so that the frame is pivoted on the 130

shaft, conveying mechanism in the frame driven by the shaft, spray mechanism carried by the frame and discharging on the conveying mechanism, a pipe leading from the spray mechanism and having its inlet end swiveled on the sleeve, a worm wheel on the shaft, a motor suspended from the sink, and a train of gearing from the motor to the worm wheel including clutch mechanism comprising a driven member operatively connected to the worm wheel and a driving member connected to the motor, the said members being juxtaposed so that they engage each other when the frame is in its lowered position and are automatically disengaged when the frame is tilted upward on its pivot.

14. In dish-washing apparatus, the combination with a sink, of a cock in the side near one end thereof, a sleeve closed at one end extending horizontally from the cock and having an outlet in the side and a shaft bearing in its closed end, a shaft bearing in the other side of the sink opposite the cock and in axial alignment therewith, a drive shaft having its ends journaled in said bearings, a frame containing bearings on said shaft so that the frame is pivoted on the shaft, conveying mechanism in the frame driven by the shaft, spray mechanism carried by the frame and discharging on the conveying mechanism, a pipe leading from the spray mechanism and having its inlet end swiveled on the sleeve, a worm wheel on the shaft, a motor suspended from the sink, a train of gearing from the motor to the worm wheel including clutch mechanism comprising a driven member operatively connected to the worm wheel and a driving member connected to the motor, the said members being juxtaposed so that they engage each other when the frame is in its lowered position and are automatically disengaged when the frame is tilted upward on its pivot, a cock in the side of the sink above the spray mechanism, a pipe extending horizontally from said last-mentioned cock, a transversely-extending spray member above the conveying mechanism, a pipe connected to said spray member, and a swivel connection between said last-mentioned pipe and the horizontally-extending pipe.

In witness whereof, I have hereunto set my hand this 4th day of August, 1928.

55 WALDEMAR L. LINDGREN.
